SPRING-RETRACTED LIP BRUSH HAVING
RAMROD MEANS IN CAP FOR PROJECTING
BRUSH TO OPERATIVE POSITIONDon Gordon, Burbank, Calif., assignor to
E. Manuel Stolaroff, Los Angeles, Calif.

Application June 12, 1948, Serial No. 32,691

2 Claims. (Cl. 15—184)

1

The present invention relates to holders for lip brushes, lipsticks, and the like, and one of its primary objects is to provide a holder which is so constructed and arranged that the article associated therewith is retracted into the body of the holder at all times except when in readiness for actual use, and is therefore protected against accidental contact. The invention is particularly advantageous in connection with lip brushes, where one of the problems is to prevent the brush hairs from contacting the inside of the closure cap. The reason for this is to prevent any excess lip rouge remaining on the brush hairs from wiping off onto the inside of the cap, from which it would transfer to the outside of the body, where it would tend to stain everything with which the body comes into contact.

I accomplish the foregoing object by mounting the brush on a spring-pressed carrier which is slidably disposed within a tubular body for movement between a normally retracted position and an extended position wherein the brush projects from one end of the body. A cap is provided which is adapted to be inserted over either end of the aforesaid body, and fixedly mounted within the cap is a pin which functions as a ramrod to push the carrier out to the extended position when the cap is inserted on the back end of the body. When the cap is removed from the back end of the body, the carrier is returned by its spring to the retracted position, and the brush hairs are then sheathed within the body when the cap is inserted on the front end thereof to close the same.

One of the principal objections to prior conventional lip brush holders having removable closure caps to protect the brush, is that sooner or later some of the lip rouge on the brush hairs wipes off onto the inside of the cap and then transfers onto the outside of the holder. The only way of avoiding this transference is to refrain from inserting the cap on the back end of the holder; but this imposes an inconvenience on the user, who, in addition to the lip brush holder and cap, is usually occupied also with the manipulation of a lipstick holder and cap, as well as a mirror. Thus, there are five separate parts which often must be handled simultaneously during the application of lipstick with a brush. The present invention alleviates this condition by permitting the cap of the lip brush holder to be mounted on the body thereof, so that the cap and body can thereafter be handled as a single consolidated item.

2

Another advantageous feature of the invention accruing from the retraction of the brush into the holder body is the elimination of all danger of disturbing or injuring the delicate brush hairs when placing the cap on the open end of the body. Since the brush hairs are completely sheathed, no particular care need be exercised when placing the cap on the body of the present lip brush holder; whereas with conventional holders it is necessary to align the cap quite accurately with the body before pushing the same into place, in order to avoid rubbing or pressing against the brush hairs with the cap. The smaller the diameter of the body and cap of conventional lip brush holders, the greater the care that must be taken when inserting the cap on the body. By eliminating all possibility of interference between the cap and brush hairs, the present invention makes it feasible to use a small diameter for the cap and body of a lip brush holder, without imposing the necessity for greater care in handling the same.

The foregoing and other objects and advantages of the invention will become apparent to those skilled in the art upon consideration of the following detailed description of the preferred embodiment thereof, reference being had to the accompanying drawings, wherein:

Figure 1 is a perspective view of a lip brush holder embodying the principles of the invention, showing the cap removed from the body;

Figure 2 is another view of the same, showing the cap inserted on the back end of the body, and the lip brush projected out to the extended position;

Figure 3 is a longitudinal section through the lip brush holder, with the cap mounted on the open end of the body to close the same;

Figure 4 is a similar view, but with the cap mounted on the back end of the body, and the lip brush extended; and

Figure 5 is an enlarged sectional view of a detail.

In the drawing, the lip brush holder of the invention is seen to comprise a body or case 10 and a cap 11, both of which are thin-walled tubular shells that are preferably drawn from sheet brass. The body 10 is open at one end, and is closed at the other end by a rounded end wall 12 having a small hole 13 formed in the center thereof.

Pressed into the open end of the body 10 is a sleeve 15 having a central bore 16. As best shown in Figure 5, the sleeve 15 is generally cylindrical in shape, and is slotted at 20 for about $\frac{3}{4}$ of its length from the back end thereof. The outside

diameter of the sleeve at 21 is made about .004" larger than the inside diameter of the body 10, and the slot 20 enables the sleeve to be compressed sufficiently to be received within the body. The outer end portion 22 of the sleeve, beyond the end of the slot 20, is made with approximately the same outside diameter as the inside diameter of the body 10, which insures that the thin walls of the latter will not be stretched by the sleeve 15 when the latter is pressed into place. The slot 20 thus provides a yielding resiliency for the oversized portion of the sleeve 15, enabling the sleeve to be assembled with a light press fit in the body 10 through a relatively wide spread of manufacturing tolerances; while the unyielding portion of the sleeve is made of the same diameter as the body so as to prevent stretching of the latter, which would necessitate selective fitting of the cap 11.

Slidably disposed within the body 10 is a lip brush carrier 25 having a tapered nose 25a onto which is pressed a tapered ferrule 26 carrying a tuft of brush hairs 27. The carrier 25 is movable between the retracted position shown in Figure 3, wherein the brush is withdrawn completely into the body 10, and the extended position shown in Figure 4. In the latter position, the ferrule and brush hairs are projected beyond the open end of the body, and the cylindrical body of the carrier 25 fills the bore 16 of the sleeve 15. At the back end of the carrier 25 is an enlarged head 28 which may be frusto-conical in shape, as shown, with either a flat or slightly concave end surface. The carrier 25 is yielding urged back to the retracted position by a soft coil spring 30 which encircles the carrier 25 and bears at one end against the bottom end of the head 28; the other end of the spring being seated on a shoulder 31 on the sleeve 15.

The carrier 25 is projected out to the extended position by the action of the cap 11 when the latter is inserted onto the back end of the body 10, and to this end the cap is provided with a longitudinally extending pin 32 which is mounted in the interior of the cap on the axis thereof, and which is adapted to pass freely through the hole 13 in the back end of the body 10. The pin 32 is pressed into a central hole 33 in a plug 34, and the latter is pressed, in turn, into the bottom end of the cap 11.

When the cap 11 is inserted on the back end of the body 10, the free end of the pin 32 passes through the hole 13 and engages the rear end of the head 28 on carrier 25. As the cap 11 is pushed further onto the body 10, the carrier 25 is pushed outwardly by the pin 32 against the pressure of the coil spring 30 until the carrier reaches a fully extended position, with the spring coils closed solidly against one another. At this point, the ferrule 26 is projected entirely beyond the end of the body 10, and the brush is in readiness for use.

In order to provide a firm frictional engagement between the body 10 and cap 11 so as to prevent the latter from being pushed off the body by the pressure of spring 30, I find it desirable to form a pair of diametrically opposed indentations 35 in the side walls of the cap adjacent the open end thereof. These indentations, known as "spring-bumps" take up the clearance between the cap and body, and provide a certain amount of interference to relative sliding movement between them; thereby creating frictional resistance sufficient to resist the pressure of the

5 spring 30. The spring-bumps 35 also engage the body 10 when the cap is mounted on the front end thereof, as shown in Figure 3, providing frictional resistance so that the cap is firmly held on the body when the lip brush holder is closed.

The telescopic movement of the cap 11 on the open front end of the body 10 is limited by means of two projections 36 which are struck out from the side walls of the body a short distance from the front end thereof. These projections are engaged by the end of the cap as the latter is pushed onto the front end of the body, stopping the cap at the position shown in Figure 3.

The operation of the invention and the many advantageous features thereof are believed to be self-evident from the foregoing description. The brush 27, being retracted entirely within the body 10 by the spring 30 when the cap is removed from the back end thereof, is protected from contact with the inside of the cap 11. With the brush 27 thus sheathed, no particular care need be exercised in placing the cap on the open end of the body. The inside of the cap 11 cannot become smeared with lip rouge from the brush, hence there is no problem of transference to the outside of the body 10. The lip brush carrier is pushed out to and solidly held in extended position by the ramrod-like action of the pin 32 when the cap is telescopically inserted on the back end of the body 10, and as the cap is removed, the carrier is retracted by the spring 30. The lip brush holder of my invention is simple and inexpensive to manufacture, as well as convenient and easy to operate.

While I have shown and described in considerable detail what I believe to be the preferred form of my invention, it is to be understood that such details are not restrictive, and that various changes may be made in the shape and arrangement of the several parts without departing from the scope of the invention, as defined in the appended claims.

I claim:

1. A retractable lip brush holder comprising a tubular case open at the front end and having a hole in the back end thereof on the axis of the case, a cylindrical carrier slidable within said case for movement between a retracted position and an extended position, said carrier having a tapered nose on the outer end thereof, a tapered ferrule pressed onto said nose, said ferrule being provided with a tuft of brush hairs, a slotted tubular bearing sleeve pressed into the open end of said case, said sleeve being the same in outside diameter as the inside diameter of said case, said sleeve frictionally engaging said case, and the portions of said sleeve on either side of the slot being squeezed together by said case, said carrier being slidable through said sleeve to said extended position so that said brush tuft is projected beyond the open end of the case, a spring contained within said case and bearing at one end on said sleeve and at the other end on said carrier to urge the latter toward said retracted position, a tubular cap adapted to be telescoped onto either end of said case, a pin fixed in the closed end of said cap and extending longitudinally along the axis thereof, the free end of said pin being inserted through said hole when the cap is telescoped onto the back end of said tubular case, said pin being engageable with said carrier to push the same out to said extended position against the pressure of said spring, and a pair of diametrically opposed indentations in 75 said cap adjacent the open ends thereof, said

indentations being engageable with the outer surface of said case to secure a firm frictional engagement thereof so as to prevent the cap from being pushed off the back end of the case by the pressure of said spring.

2. In a retractable lip brush holder, the combination of: an elongated tubular case comprising a tubular member having a cylindrical bore opening through the front end thereof, an end closure at the back end thereof formed with a hole on its longitudinal axis, and a tubular bearing sleeve pressed with a friction tight fit into the front end thereof, the inner end of said sleeve affording an annular inwardly facing seating shoulder, a carrier movable longitudinally within said tubular member formed with an intermediate cylindrical section slidable within said bearing sleeve, an enlarged head formed on the inner end of said cylindrical section of said carrier slidable inside said tubular case in sliding engagement with the wall surface of said cylindrical bore, said enlarged head affording a shoulder at its juncture with said cylindrical section which faces toward said bearing sleeve, and a reduced nose on the outer end of said carrier, a coil spring inside said tubular member encircling said cylindrical section of said carrier and seated at opposite ends against said shoulder afforded by said sleeve and said shoulder afforded by said enlarged head, a ferrule pressed onto said nose,

10
15
20
30

said ferrule being provided with a tuft of brush hairs, and a tubular cap for the open end of said case arranged also to be telescoped with a frictional longitudinally sliding fit onto the back end of said tubular case, and a pin fixed in the closed end of said cap and extending longitudinally along the axis thereof, the free end of said pin being received through said hole when the cap is telescoped onto the back end of said tubular case, said pin being directly engageable with the head on said carrier to push the same against the restraint of said spring out to an extended position with said ferrule protruding from said bearing sleeve, said carrier being retractible by said spring when said cap is removed from the back end of said case to a retracted position with said brush hairs received inside said bearing sleeve.
